SHIELDING ARRANGEMENT FOR A REED RELAY
Ralph Morrison, Pasadena, Calif., assignor to Dynamics
Instrumentation Company, a corporation of California
Filed July 1, 1966, Ser. No. 562,391
12 Claims. (Cl. 335—151)

The present invention relates to an improved reed relay structure capable of manipulating electrical current paths by the operation of electrical switching signals, wherein the switching signals have relatively little effect on signals carried by the current paths and wherein capacitive coupling across relay contacts is reduced.

Reed relays are one of the many different types of switching devices widely used in the electrical arts. In general, these relays comprise magnetizable conductive reeds cantilevered to extend inwardly from the ends of a hermetically-sealed glass envelope so that the free ends of the reeds are spaced-apart in overlapping relationship. A coil conventionally mounted on the glass envelope may then be energized to provide a magnetic field that magnetizes the reeds, so they come together into electrical contact. Both single-throw and double-throw relays have been used in the past.

In general, reed relays have been considered relatively simple, compact reliable and inexpensive to manufacture. Furthermore, such relays are responsive in applications involving control signals of relatively low power. In such applications, the controlled current paths generally have been considered relatively free from spurious signals induced by the control or switching signals. However, at the present advanced state of various electrical arts (including the field of electronic instrumentation) a need exists for a switching mechanism or relay wherein the controlled current paths are more-completely isolated from control signals applied to the relay as well as open-circuit signal coupling. That is, the need exists to control current paths for signals which are very small in relation to the switching signals. Therefore, the paths of the switching signals e.g. the coil, must be effectively isolated from the paths of the controlled signals. Furthermore, the signal paths must be effectively isolated at the location of interruption. Still further, a considerable need exists for a structure of the type described which can be economically manufactured with relatively uniform operating characteristics.

It is therefore an object of the present invention to provide an improved reed relay structure incorporating an effective shielding arrangement with the result that control signals are less productive of spurious signals in the controlled current paths.

Another object of the present invention is to provide an improved electro-magnetic reed relay structure which may be inexpensively manufactured.

Still another object of the present invention is to provide an improved reed relay structure having considerably-reduced mutual capacitance between the elements thereof, and which is therefore capable of employing control signals for switching controlled signals of extremely low power, without appreciable noise contamination.

A further object of the present invention is to provide an improved reed relay structure wherein a peculiar shielding material is employed, which material is economical and effective in operation.

Still a further object of the present invention is to provide an improved reed relay structure incorporating a plurality of current paths, at least one of which contains switching contacts, and which current paths are effectively shielded by conductive cylinders, whereby to reduce capacitive coupling as with the magnetic element of the relay.

2

One other object of the present invention is to provide an improved reed relay structure in which capacitive signal coupling between open contacts is reduced.

These and other objects and advantages of the present invention will become apparent from a consideration of the following, taken in conjunction with the drawings, wherein:

FIGURE 1 is a perspective view of a reed relay constructed in accordance with the principles of the present invention;

FIGURE 2 is a fragmentary vertical sectional view taken along the central axis of the cylindrical structure of FIGURE 1;

FIGURE 3 is a sectional view taken transversely through the structure of FIGURE 1;

FIGURE 4 is a diagrammatic representation of an illustrative structure incorporating the principles of the present invention;

FIGURE 5 is a sectionalized plan and diagrammatic view of an alternative structure in accordance with the present invention; and

FIGURE 6 is a diagrammatic representation of a system incorporating a structure somewhat similar that of FIGURE 5.

Referring initially to FIGURE 1, there is shown a generally cylindrical body 12 comprising the reed relay, which coaxially receives a conductor 14 in one end 16 and a conductor 20 in the other end 18. The conductors 14 and 20 are connected and disconnected as considered below, under control of a switching signal applied across a pair of conductors 22 and 24.

A second current path through the body 12 is provided by a single integral conductor 26 passing through the body 12 parallel the conductors 14 and 20 and providing a return path for currents controlled by the internal switch. The connection of conductors 14 and 20 by the internal switch of the reed relay is accomplished by a magnetic field developed by current flowing through the input conductors 22 and 24 to a magnetic coil.

In prior reed-relay structures, the magnetic coil has tended to create spurious signals in the switching circuit as a result of capacitive coupling. Although some prior shields have been proposed, a need has continued to exist in many applications for a more effective structure to shield against capacitive coupling. The detailed structure of an exemplary shielding arrangement hereof is described below; however, it is here noteworthy that conductors 28, one pair extending from each of the ends 16 and 20 of the body 12, provide electrical contact to shield members within the body 12.

Functionally, the illustrative component represented in FIGURE 1 switches current flow (open or closed circuit) between the conductors 14 and 20 in accordance with a switching signal applied across the conductors 22 and 24. Furthermore, effective shielding is provided within the component and the shielding structure may be variously connected to reference potential sources through the conductors 28. The component structure also provides a shielded return line in the form of the conductor 26 which is effective for use in many applications in cooperation with the internal shields.

Considering the structure of the unit in greater detail, reference will now be made to FIGURES 2 and 3. Generally, the component structure comprises a group of concentric cylinders positioned about the central electrical switching contacts. The conductor 14 is connected to, or becomes a reed contact 30 (FIGURE 3) inside the sealed enclosure 34. That is, the conductor 14 may be integral with the reed contact 30, or alternatively these members may be separately formed and joined by a junc-

tion 31 (FIGURE 2) as shown connecting the reed contact 32 to the conductor 20, outside the enclosure 34.

Various forms of reed contacts are well known in the prior art. Generally they are formed of a strip of flexible or resiliently deformable paramagnetic metal and are shaped to be disconnected (FIGURE 2) when in a quiescent state. Upon the application of the switching current to the component, a magnetic switching field is developed and the contacts 30 and 32 move into aligned electrical contact.

The enclosure 34 housing the contacts 30 and 32 is of generally cylindrical configuration and may be formed of glass, having glass-to-metal seals in the ends thereof to support the reed contacts 30 and 32 and pass them to their respective junctions 31. The solid conductor 26 (FIGURE 2) operates in cooperative relationship with the reed contacts 30 and 31, lies contiguous to the glass enclosure 34 and is encompassed by a cylinder 36 of insulating material of a flexible or resilient nature, e.g. Mylar. Concentric cylinders are then placed about the insulating cylinder 36 to provide spaced-apart co-axial shields in the component structure. More specifically, in their order of occurrence from the cylinder 36, the following cylinders are provided; a conducting cylinder 38; an insulating cylinder 40; a conducting cylinder 42 and an insulating cylinder 44.

The insulating cylinders all may be similar (in material and form) to the cylinder 36, e.g. comprising Mylar. The conducting cylinders 38 and 42 may comprise a conducting fiber or paper material which has a specific resistance across points in any given area relationship. One example of a material suitable for the cylinders 38 and 42 is manufactured by the Minnesota Mining and Manufacturing Company, and is designated resistance or conductive paper X1175. The use of conductive paper in this application is not only economical in cost and fabrication but also provides shielding of an effective nature in the structure hereof.

Pursuing consideration of the detailed structure of the component element, the conductive cylinders 38 and 42 are connected at each end to the conductors 28 for providing individual electrical contact outside the body 12. Additionally, a conductor 28a (FIGURE 2) extends through the body, parallel the cylindrical axis and between the cylinders 36 and 38, connected at both ends to the conductors 28.

Electrical conductors 22 and 24 (FIGURE 1) for carrying switching signals, are connected to a cylindrical coil 46 (FIGURE 3) provided outside the cylinder 44 in concentric relationship to the other cylinders. The coil 46 provides the magnetic field to displace the reed for switching operations.

The concentric electrical structure (FIGURE 2) as described above is housed or embedded in a closure 48 which may comprise epoxy resin or various other insulating materials. Thus, the structure is substantially isolated from the effects of ambient environments.

In the manufacture of the component as shown in FIGURES 1, 2 and 3 the central structure may be formed as a sub-assembly providing the reed contacts 30 and 32 sealed in the glass enclosure 34 with connecting junctions 31 to the conductors 14 and 20 respectively by using various well known techniques of the prior art. Next, the concentric cylinders may be provided about the enclosure 34 with the conductors 26 and 28a held in position therein. In this regard, a single wrap of the various materials considered may be provided with seams 50 as shown in FIGURE 3 to accomplish the cylinders. It may be desirable to angularly offset the various seams 50 to provide space compensation; however, such a consideration is only of incidental significance hereto.

The sheets forming the conductive cylinders 38 and 42 carry connection tabs 52 and 54 (FIGURE 2) at each end which are in turn connected to the ends of the conductors 28a and the interconnected conductors 28. More

specifically, a conductive adhesive 55 is applied to a small area of the sheets comprising the cylinders 38 and 42 by which the conductive tabs 52 and 54 are then affixed to the cylinders. The tabs 52 and 54 may comprise small sheets of copper or other conductive sheets which provide a base connection for the conductors 28 and 28a. This connection may be provided by soldering or various other techniques well known in the prior art.

Upon completion of the internal-cylindrical sub-assembly as described above, the coil 46 is telescopically positioned thereon. The coil may be pre-wound as a sub-assembly and placed on the cylindrical assembly, or it may be wound directly on the partial assembly. The coil 46 is connected to the energizing conductors 22 and 24 as previously explained. Next, the assembly is encapsulated within the closure 48 as with epoxy potting compound, so that the extending conductors lie outside the closure.

Thus, the component is completed and ready for use. As indicated above, the reed contacts 30 and 32 (FIGURE 2) are formed to lie spaced apart in the quiescent state of operation; however, upon application a sufficient electrical current to the coil 46 through the conductors 22 and 24 (FIGURE 1) a magnetic field is established which magnetizes the reed contacts 30 and 32 (FIGURE 2) moving them into aligned engagement and thereby closing the circuit between the conductors 14 and 20 (FIGURE 1). Removal of the magnetic field, by halting current flow in the coil 46, allows the contacts 30 and 32 to spread, opening the circuit.

Considering a particular circuit hereof utilizing the structure hereof, reference will now be made the diagram of FIGURE 4, which illustrates the shield elements as well as the active signal paths. The reed relay element as described above is schematically represented in the block 58, the reed contacts 30 and 32 being shown simply as a switch 60. In a similar schematic fashion, the coil 46 is represented as are the conductive cylinders 38 and 42.

The coil 46 (FIGURE 4) is connected through a switch 62 across a source of potential that is applied to terminals 64. Therefore, closure of the switch 62 energizes the coil 46 to close the switch 60, thereby completing the signal path from a transducer 66, through an amplifier 68 to output terminals 70. The transducer 66 is provided within a shield 72 (grounded through a capacitor 73) which also encloses conductors 74 and 76, that extend to the conductors 14 and 26 respectively, as described with reference to FIGURE 1. The shield 72 is also connected to the cylinder 38 and then through conductor 28a. At the amplifier side, a shield 73 is provided over the amplifier 68 and conductors thereto. The shield 73 is connected to the through conductor 28a and the cylinder 38 and grounded along with the cylinder 42.

It is to be noted that the structure hereof enables the use of a ground return conductor, i.e. conductor 26, to be used as part of a signal return path thereby reducing the magnetic pickup from the operating coil which avoids reliance upon the shield structure as a ground return. This mode of operation is extremely effective in many applications involving critical signals, particularly in cooperation with shields as described.

Regarding the avoidance of spurious signals in the conductors 14, 20 and 26 resulting from the energization of the coil 46, an internal conductive cylinder 38 cooperatively acts as a secondary shield. In function, the second shield diverts a second set of shield currents, so that these currents do not enter the signal-carrying structure. As a result, significant improvement is provided.

In some applications, capacitive coupling between switch contacts has been found to be a problem. For example, when the switch 60 (FIGURE 4) is open, the reed contacts are capacitively coupled to a degree which has been recognized to present a problem. This difficulty can be avoided by utilization of an alternative embodiment

hereof as shown in FIGURES 5 and 6 and as will now be considered in detail.

The external coil and shield structure for providing the magnetic field in the embodiment of FIGURE 5 and shielding the elements may be similar to that previously described and is therefore symbolically represented as a cylindrical coil and shield structure 90. Inside the structure 90 there is provided a glass enclosure 92 of tubular form and having closed ends 96 and 98 which support the reed contacts. These contacts provide a double-pole single-throw switch between conductors 100 and 102 at the end 96 and conductors 104 and 108 at the end 98. The functional switch is shown in a quiescent or open state.

The conductors 100 and 102 are affixed to reed contacts 110 and 112 respectively. In a similar manner, the conductors 104 and 108 are affixed to reed contacts 114 and 116 at the other end of the enclosure 92. When the relay is closed or made, the contacts 110 and 114 are interconnected, as are the contacts 112 and 116. However, when the relay is open, these contacts are not only ohmically isolated but additionally the leakage capacitance therebetween terminates on a central structure 118 which is normally connected through a wire 120 (extending through the end 98) to ground potential.

The central structure includes a spacer support 122 of disk configuration, formed of insulating material, as ceramic for example and serving to hold several of the reed contacts. Specifically, as shown, at the top of the support 122 there is a reed contact 124 extending from the support to engage the contacts 110 and 114 upon energization of the relay. A reed contact 126 is fixed to electrically engage the contact 124 in the support 112, and extends to normally engage a contact 128 which is also cantilevered from the support 122 and is connected to a through reed contact 130 extending to engage the contacts 112 and 116 when the relay is energized. The reed contact 130 is also fixed in connection to a reed contact 132 which normally engages a reed contact 134, both of the latter being cantilevered from the support 122 for mutual contact when the relay is not energized.

In producing the relay as shown, the shield and coil structure 90 may be formed as previously described on the glass enclosure 92. Inside the enclosure 92 the central structure 118 may be produced by molding the support 122 with the identified contacts in position as well known in the prior art. Thereafter the glass enclosure may be placed about the various contacts.

When the relay is in an unenergized state with the two controlled paths therethrough open (contacts positioned as shown) the reed contact 124 is connected through the contacts 126 and 128 to the contact 130, which is in turn connected to the ground wire 120 through the contacts 132 and 134. Therefore, both the reed contacts 124 and 130 are connected to ground so as to terminate leakage capacitance to the contacts 110, 112, 114 and 116. As a result, considerable improvement occurs in the isolation of the reed contacts 110, 114, 112 and 116.

Of course, the concepts of the reed relay as illustrated in FIGURE 5 may be variously embodied in a wide variety of different specific structures. For example, the pair 60 of reed-contact switching paths may be expanded to an increased plurality, as may the pair of through contacts embodied in the structure 90 (shown in detail in FIGURE 2). Furthermore, the isolation of the contacts by terminating capacitance at a central structure can be variously accomplished. One structural form of such a variation is symbolically represented in FIGURE 6, which also discloses another circuit embodiment hereof.

The reed relay 140 (FIGURE 6) is symbolically represented to include: a drive coil 142; concentric shields 144 and 146 (which may be physically similar the shield cylinders 38 and 42 of FIGURES 2 and 3) and a plurality of reed contacts 148 which are housed for motivation by the field of the coil 142. The reed contacts 148 are shown in 75

the state when the coil 142 is de-energized. The arrangement of the reed contacts 148 is an alternative, functionally similar variation of the structure of FIGURE 5. Specifically, one end 150 (symbolically represented) of the relay enclosure passes reed contacts 152, 154 and 156. The other end 158 passes reed contacts 160, 162 and 164. A central structure (as shown in FIGURE 5) supports the intermediate contacts. Specifically, one movable contact 166 serves as a double-throw switch in cooperation with the fixed contact 152 and a fixed contact 168. The movable contact 166 is connected to a movable contact 170 which engages the contact 160 when the relay is energized.

The stationary contact 168 is connected to a movable contact 174 which comprises a double-throw switch with stationary contacts 154 and 164. The contact 174 is also connected to a stationary contact 180 which engages the contact 162 when the relay is energized. The stationary contact 164 is also connected to a movable contact 184 which engages the contact 156 when the relay is not energized.

The input to the relay 140 is from a signal source 190 which is coupled between contacts 152 and 154 by resistors 192 and 194 respectively. The junction point 196 between the signal source 190 and the resistor 194 is connected to ground along with a shield 198 which extends substantially to the relay 140 and is electrically connected to the shield 144 and to the contact 156.

In the operation of the system as shown in FIGURE 5, it is apparent that when the coil 142 is not energized (as depicted) the contacts 152 and 154 are not engaged. However, it is also apparent that capacitive coupling exists from these contacts to the contacts 166 and 174 respectively. Therefore, in accordance herewith, the contacts 166 and 174 are connected to ground potential. Specifically, the contacts 166 is coupled to ground potential through contacts 168, 174, 184 and 156. The contact 174 is ground connected through a similar path. In this regard, it is to be noted that the contacts 170 and 180 (engaged by output contacts 160 and 162) are also grounded to effect isolation.

At a time when the relay coil 142 is energized by application of a potential to a terminal 202, the movable elements of the contacts 148 are displaced into axial alignment with the cylindrical relay. Specifically, contacts 170 and 184 drop down from the positions shown while contacts 162, 166, and 174 rise. As a result, a current path from the resistor 192 is established through contacts 152, 166, 170 and 160 to the output terminal 204. Similarly, a current path from the resistor 194 is established through the contacts 154, 174, 180 and 162 to the output terminal 206. It may be noted that these current paths are isolated from any grounded contacts in the structure.

It is therefore apparent, that the system hereof provides an effective switching unit for highly critical electrical signals and is particularly applicable in systems in which very little distortion can be tolerated. In particular, this capability stems primarily from such structural features as: the use of through conductors interior of the energizing coil, two electrostatic shields, plural reed switches in the relay, and provision of a central grounding section for terminating contact capacitance.

The system hereof also provides a unit which can be manufactured in a very small physical configuration, and which is economical, and exceedingly rugged. Of course, various other features and advantages of the structure will be readily apparent to persons skilled in the art, which persons will also readily perceive various other structural forms for the conceptual configuration. As a result, the scope hereof is not to be limited in accordance with the specific illustrative embodiments shown and described herein as exemplary forms of the invention, but rather shall be defined in accordance with the claims as set forth below, forming a part of this application.

What is claimed is:

1. A reed relay structure wherein at least one current path is controlled in accordance with control signals, comprising:
  - a set of reed contacts adapted to be connected in said current path;
  - a magnetic coil means for controlling said reed contacts to be opened and closed;
  - a first conductive shield fixed about said set of reed contacts;
  - a second conductive shield fixed about said first conductive shield; and
  - insulation means for ohmically isolating said first and said second conductive shields.
2. A reed relay structure according to claim 1 wherein said conductive shields comprise cylinders of conductive paper.
3. A reed relay structure according to claim 2 further comprising connection leads affixed to said conductive paper and wherein said conductive paper has a resistance of at least ten ohms per inch.
4. A reed relay structure according to claim 1 further including a conductor extending substantially parallel to said set of reed contacts to be used as a part of the signal return path to reduce the magnetic pickup from the operating coil.
5. A reed relay structure according to claim 4 wherein said conductive shields comprise conductive paper having a resistance of at least 10 ohms per inch and further including terminal conductors affixed to said conductive shields.
6. A reed relay structure according to claim 5 further including input signal means for providing a signal between said conductor and one of said reed contacts and further including means connecting said first shield.

7. A reed relay structure according to claim 2 wherein said insulation means comprises a Mylar-like plastic material.

8. A reed relay structure according to claim 7, further comprising connection leads affixed to said conductive paper and wherein said conductive paper has a resistance of at least ten ohms per inch; and further including a conductor extending substantially parallel to said set of reed contacts to be used as a part of the signal return path to reduce the magnetic pickup from the operating coil.

9. A reed relay according to claim 1 including a plurality of sets of reed contacts whereby when said relay is open, certain of said reed contacts intermediate other of said reed contacts provide capacitive termination.

10. A reed relay according to claim 1 further comprising a plurality of through conductors extending through said magnetic coil means.

11. A reed relay according to claim 1 wherein a plurality of current paths therethrough and therefore including additional sets of reed contacts.

12. A reed relay according to claim 11 including a plurality of sets of reed contacts whereby when said relay is open, certain of said reed contacts intermediate other of said reed contacts provide capacitive termination.
